CLAIM

The ornamental design for a magnetic cutlery holder as shown and described.

DESCRIPTION

FIG. 1 is a rear perspective view of the magnetic cutlery holder of the instant invention;

FIG. 2 is a left front perspective view thereof;

FIG. 3 is a right front perspective view thereof;

FIG. 4 is a top right perspective view thereof;

FIG. 5 is a top plane view thereof, the bottom view forming a mirror image, not shown;

FIG. 6 is an end plane view thereof, the opposite end forming a mirror image, not shown; and,

FIG. 7 is an elevational view of the magnetic cutlery holder. The broken lines in FIG. 1 show portions of the magnetic cutlery holder that form no part of the claimed design. The broken lines in FIG. 7 show environmental subject matter that forms no part of the claimed design.

1 Claim, 7 Drawing Sheets
